I. GOODSPEED.

Burglar Alarm.

No. 26,001.

Patented Nov. 1, 1859.

UNITED STATES PATENT OFFICE.

ISAAC GOODSPEED, OF NORWICH, CONNECTICUT, ASSIGNOR TO HIMSELF, AND GEO. A. MANSFIELD, OF BOSTON, MASSACHUSETTS.

POCKET-ALARM.

Specification of Letters Patent No. 26,001, dated November 1, 1859.

To all whom it may concern:

Be it known that I, ISAAC GOODSPEED, of Norwich, New London county, Connecticut, have invented a new and useful Pocket, 5 Thief, and Burglar Alarm, and that the following description, with the accompanying drawings, form a full, clear, and exact specification thereof.

My invention consists in the production 10 and manufacture of my pocket alarm, which consists of a shell or case of such form and size, as to be conveniently carried about the person with suitable mechanism inclosed therein for causing the explosion of a per- 15 cussion cap upon the removal of any article to which the alarm is attached.

The accompanying drawings represent my machine.

Similar letters represent similar parts in 20 all the views.

Figure 1, is an exterior side elevation of the machine. Fig. 2 is a edge view of ditto. Fig. 3 is a side view with outer casing next the observer removed, to exhibit the interior 25 mechanism.

a, represents the external case.

b, represents the hammer.

c, represents the cap tube.

d, represents the cap on the tube.

e, represents the main spring.

f, represents the cocking catch.

g, represents the hitching string having a pin *h*, at its ends.

i, represents the trigger string, having a 35 hook *j*, at its ends.

k, represents a small lever used for cocking the machine by inesrting its small end *l*, into a hole *m*, in the end of the hammer. It is also used for placing the cap on the cap- 40 tube, the cap being held by the jaws of the cleft end *n*.

Figs. 4 and 5, are illustrative views showing some of the various methods in which the machine may be applied.

45 Fig. 4 represents a man about being robbed of his pocket book by the hand of a

thief, but having taken the precaution to provide himself with one of my alarms with the hitching string *g*, secured to the pocket book, and the trigger string *i*, hooked to the 50 side of his pockets, or any contiguous part of his clothing, no sooner does the thief pull on the pocket book than the alarm explodes, and thus gives prompt notice to the intended victim, and to the bystanders also, of his in- 55 tended robbery.

Fig. 5, shows the application of my machine, as a burglar alarm, being attached to the inside of the door, of a room in which a traveler is supposed to have retired for the 60 night. The hitching string is pinned rather slightly by the pin *h*, to the casing of the door, while the trigger string is hooked to the door itself, taking care to leave the trigger string one or two inches slack. No sooner 65 does an intruder open the door a little, than the pin *h*, is pulled out, and the weight of machine causes a strain on the trigger string, and an explosion immediately takes place, 70 alarming the inmates of this and probably of the neighboring rooms.

Ingenuity and due presence of mind and precaution would undoubtedly suggest a great variety of other particular circumstances, in which the possessor of such an 75 article could apply the same to the security of his person and property, while the whole machine for convenience is capable of being reduced to a very diminutive bulk, without impairing its efficiency.

80 In the pocket, thief, and burglar alarm constructed in the form and manner represented and described, I claim—

The combination and arrangement of the independent lever *k*, adapted to cap and 85 cock the alarm, while both the cap-tube and hammer are arranged within and do not project outside the shell or case.

ISAAC GOODSPEED.
